UNITED STATES PATENT OFFICE.

JOHN C. BERTSCH, OF EDGEWOOD PARK, PENNSYLVANIA.

REFRIGERATING APPARATUS AND REGULATOR.

1,247,209.

Specification of Letters Patent. Patented Nov. 20, 1917.

Application filed October 8, 1915. Serial No. 54,783.

To all whom it may concern:

Be it known that I, JOHN C. BERTSCH, a citizen of the United States, and a resident of Edgewood Park, in the county of Allegheny and State of Pennsylvania, have made a new and useful Invention in Refrigerating Apparatus and Regulators, of which the following is a specification.

This invention relates to improvements in refrigerating apparatus of the compression system, in which a volatile fluid is alternately vaporized and condensed or liquefied.

The chief object of this invention is to provide simple and cheap means for controlling the operation of a refrigerating apparatus which renders it automatic without the necessity of employing external auxiliary controlling devices.

Another object is to provide means by means of which the condenser and evaporator, each independent of the other, controls its own pressures and at the same time acts as its own safety device.

Still another object of this invention is the automatic removal of any lubricant which may be carried into the evaporator.

Other objects and advantages of this invention will be fully explained in the following specification and be pointed out in the claims.

The accompanying drawings illustrate a form of this invention most suitable for domestic installations, together with details of construction and some modifications required for industrial purposes.

Figure 1 is a vertical section through the center and at right angles with the compressor axis of a domestic apparatus.

Fig. 2 is a horizontal section along line 2-2 of Fig. 1.

Fig. 3 is an enlarged detail of the fluid regulating valve within the evaporator.

Fig. 4 is a cross section along line 3-3 of Fig. 3.

Fig. 5 is a vertical section through the center and along the axis of the compressor of a domestic apparatus.

Fig. 6 is a top view of the apparatus shown in Figs. 1 and 5 with the cover removed.

Fig. 7 is a cross section along line 4-4 of Fig. 5.

Figs. 8 and 9 are details showing the construction of the collapsible vessels forming evaporator and condenser.

Fig. 10 is an enlarged vertical section through the lubricant return pump, within the evaporator.

Fig. 11 is a cross section along line 5-5 of Fig. 10.

Fig. 12 is a diagram showing the application of this invention to a combination apparatus for industrial purposes.

Fig. 13 is an elevation of an evaporator or condenser consisting of a number of collapsible vessels.

Fig. 14 is a plan view of an evaporator or condenser shown in Fig. 13.

The apparatus illustrated in the accompanying drawings includes a compressor of the type in which lubricant, such as water, glycerin, or a similar liquid is delivered to the working passages and the apparatus is adapted to employ a refrigerant liquid or fluid, such for example, as ethyl chlorid, rhigolene lighter than the lubricant employed in the compressor. It must be understood, however, that with very slight modifications fluids heavier than the lubricant may be employed, such as carbon tetrachlorid, or the like, without departing from the spirit and scope of this invention as set forth by the appended claims.

The apparatus illustrated includes a pump or compressor generally indicated by A in Fig. 1, which withdraws vaporized or gaseous refrigerant from a vaporizer, generally indicated at 28 and compresses the fluid so withdrawn into a condenser, generally indicated at 20 in Fig. 1. The condenser is provided with a lubricant separator (hereinafter fully described) since, with the type of compressor illustrated, lubricant is apt to be and in fact will be delivered with the refrigerant from the compressor to the condenser. While the construction, arrangement and location of the separator forms a part of the present invention, it will be apparent that it may be dispensed with where other types of compressors are employed, and I therefore desire it to be understood that the broad invention herein set forth is independent of the separator.

The vaporizer illustrated in Fig. 1 communicates with the fluid intake of the compressor and is provided with a refrigerant delivery valve, which controls the delivery of refrigerant to vaporizer in accordance with variations in the pressure within it. This is accomplished in a novel manner, as will

hereinafter be described in detail, by so constructing the vaporizer that it is provided with a flexible or collapsible wall which is adapted to vary its relative position in response to variations of internal pressure and to thereby control the operation of the refrigerant delivery valve. The vaporizer is adapted to be surrounded by the refrigerating liquid or fluid to be cooled, and may form 5 a part of a vaporizing system such as is ordinarily employed in refrigerating apparatus and such as is illustrated in Fig. 12.

The condenser illustrated also forms a novel and important feature of my invention 15 in that it operates to control the delivery of condensing water or cooling liquid in response to variations of pressure encountered within its interior. As illustrated, the condenser consists of an inclosed vessel similar 20 to the vaporizer, having a flexible or collapsible wall which is adapted to occupy different positions in response to variations in the pressure within the condenser and to control or actuate the cooling water or liquid 25 delivery valve. As illustrated in Fig. 1 a condensing chamber, provided with a flexible or collapsible wall may form the entire condenser for the apparatus, or it may form 30 a part of an ordinary condensing system such as is illustrated in Fig. 12.

Referring now to the drawings by means of the reference numerals; a casting 10 forms the base of the apparatus and also the housing of the rotary compressor, which 35 may be of any well known construction as far as the internal working parts are concerned. The housing 10 contains the compressor cylinder 11; the suction chamber 12, the lubricant return chamber 13, the discharge chamber 14, the fluid chamber 15 and the lubricant chamber 16.

The cylinder 11 is closed by a cylinder head 17 (see Fig. 7), which contains another lubricant chamber 16^a, connected with chamber 16 by a passage 18 (see Fig. 5). On top of the housing 10 is a flanged neck 19, (Figs. 1 and 5), which carries the condenser 20, and within the latter a separator 21.

Discharge chamber 14 is provided with a 50 discharge pipe 22 through which the compressed mixture of lubricant and fluid-gas is discharged into the separator 21 where separation takes place, the lubricant passing through passages 23 into chambers 16 and 55 16^a, and the gas passing through holes 24 into the condenser 20 for being liquefied by the action of the cooling water on the outside of the condenser.

The liquid passes then through port 25 60 into the liquid chamber 15 and from there through pipe 26 and regulating valve 27 into the evaporator 28. Within the latter the liquid is vaporized by the heat supplied by the cold carrier, such as water, 65 brine, or the like, contained in a tank 29, in

which the evaporator is immersed. The vapor resulting from said vaporization is drawn into the rotary compressor through vapor pipe 30 and suction chamber 12, and after being compressed, is discharged into the condenser 20 as stated above, and for the purpose mentioned, thus completing the entire cycle of operation. 70

A water jacket 31 surrounding completely the housing 10 and condenser 20, is supplied with cooling water through valve 32. 75

The cooling water cools first the housing 10 with all its chambers and their contents, and then in a counter-current fashion, the gas within the condenser, leaving the apparatus 80 by overflowing into a funnel 33 and passing out through outlet 34, as shown in Figs. 1 and 5.

The successful operation and economy of a refrigerating apparatus, particularly for 85 domestic and small industrial purposes, depends entirely upon the closest regulation of the fluid supply to the evaporator and water supply to the condenser, which keep the pressures within both in proper relation to the temperatures. 90

For such a close regulation, a great number of auxiliary devices with more or less delicate mechanisms have been proposed, without furnishing simple and reliable 95 means for the end in view. The regulating devices used heretofore consist chiefly of diaphragms, so-called "balanced valves," or electrical devices. In most cases, the diaphragms are too weak and limited in their movement for a great range of pressures, and when used in connection with evaporators, that part open to the atmosphere becomes frosted and covered with ice, thus putting the whole apparatus out of commission, or at least impairing the proper 100 regulation. The balanced valves produce much friction, and the least grit or change in the viscosity of the lubricant or fluid prevents their proper action. 105

The electrical devices invariably are put 110 out of order by the deposit of moisture present in or around refrigerators, leaving the apparatus in uncontrollable condition. Neither one of these older devices serves as a reliable and safe regulator, and besides, they are mostly too complicated and expensive to be handled by unskilled persons.

To eliminate all of these defects, I employ the inherent power of the expansion and contraction of the fluid upon large surfaces, gained by replacing the customary pipe coils used for evaporator and condenser, in part or as a whole, by collapsible vessels, as shown in Figs. 1, 5, 12, 13 and 14. These 115 vessels may be constructed of any suitable material, such as brass, copper, steel, or the like, in any required size, for any pressures, and in forms as shown in Figs. 8 and 9, or any similar shape. I employ these collapsi- 120 130

ble vessels either in single units, as shown as condenser in Figs. 1 and 5, or in duplex units, as shown as evaporator in Fig. 1, or in multiple single or duplex units for either 5 condenser or evaporator, as shown in Figs. 13 and 14, depending entirely upon the service demanded or surfaces required. For larger, or in existing installations, these collapsible vessels may be used in connection 10 with pipe coils, located either around or above or below, or on the side of the former, as in part indicated by the diagram of Fig. 12. In all cases, one single unit of collapsible vessel, for each condenser and evaporator, is sufficient for carrying the means required for the regulation of the apparatus. 15

The collapsible condenser 20 is provided on top with a hinged lever 35, rod 36, and adjusting screw 37, (Figs. 5 and 6) for the 20 automatic regulation of the water inlet valve 32. When the apparatus is at rest or just stopping, the pressure within the condenser 20 decreases and the collapsible vessel contracts, thereby closing the water valve 32. 25 When starting or operating, the pressure within the condenser increases, and after reaching a predetermined height, the collapsible vessel has expanded enough to open gradually the water valve 32 by lever 35 and rod 36, until equilibrium exists between the 30 pressure and the corresponding temperature produced by the flowing cooling water. After this, the least increase in pressure expands the collapsible vessel more and the 35 lever 35 and rod 36 open the valve 32 wider, so that more water flows, and the least decrease in pressure causes the collapsible vessel to contract, thereby closing the valve 32 a little and supplying less water to the 40 condenser. But in case of excessive pressure the collapsible vessel expands to its limit stop and thereby opens the valve 32 wide, so that at once a sufficient amount of water 45 flows to the condenser to overcome the high pressure by instant cooling. If the temperature of the cooling water changes to a higher or lower one, the quantity of water is automatically increased or decreased respectively, so that the proper and predetermined 50 pressure is always maintained regardless of the fluctuations in both the temperature of the cooling water and pressure in the condenser.

It is evident that this method of regulation is positive and results in a perfectly safe operation as well as in a great economy in cooling water.

If more than one condenser unit is employed, as indicated in diagram Fig. 12, the 60 collapsible condenser 20 as a part of the whole condenser, may be provided with as many levers 35 as there are condenser units, so that each unit is controlled independently from the others with reference to the water 65 supply. The location of the water valves

32 may be at any convenient place in reach of a lever or rod connected to a link or lever on top of the collapsible vessel forming a part of the whole condenser.

Each collapsible vessel is provided with 70 a suitable limit stop, both for contraction and expansion (not shown), in order to keep their movement within safe and proper limits.

If the collapsible vessel forms the whole 75 of the condenser, it must be immersed in the cooling water, whereas in cases where it forms only a part of the whole condenser as indicated in Fig. 12, the immersion of the collapsible vessel may be dispensed with 80 without detracting any of its working or controlling qualities, but simply losing the cooling value of its surfaces.

The very same principles just described for the collapsible condenser 20 hold equally 85 well for the collapsible evaporator 28, with the only difference that all collapsible vessels used as evaporators must always be immersed within the cold carrier in order to prevent their covering with frost or ice. 90

In the evaporator, the collapsible vessel regulates by its expansion and contraction the flow of the liquid fluid into the evaporator, and at the same time pumps automatically any lubricant which may get into the 95 evaporator out of the latter and into the rotary compressor. The means for both of these operations are located within the collapsible vessel, being adjustable from without for any desired service. 100

For the regulation of the flow of liquid fluid into the evaporator, liquid pipe 26 is rigidly connected to the top of the collapsible vessel 28 (Figs. 1, 3 and 5) extending within said vessel and terminating in a cylinder which fits slidably into a sleeve 38. The latter is supported by a screw 39 which rests within collars in the top wall of vessel 28, turning in the latter, and is protected against the atmosphere by a cap 40 which 110 fits tightly to vessel 28.

Sleeve 38 has one or more slots, 41, through which the fluid must pass on its way to the evaporator 28, and may be adjusted up or down by the screw 39. To the 115 bottom of vessel 28 is rigidly connected plate 42, carrying a stem 43 which supports a perforated cap 44. The plate 42 forms the cover of an opening through which the cap 44 can pass for assembly and repair. Cap 120 44 fits slidably over slotted sleeve 38, and opens and closes with its inner edge the ports 41 by the expansion and contraction of the collapsible wall of vessel 28. While the apparatus is at rest or just starting, the 125 pressure within the vessel 28 is much greater than while under operating condition, hence it is expanded, and the cap 44 closes completely the ports 41. During the operation of the apparatus the pressure within vessel 130

28 is reduced and the vessel contracted, until the ports 41 begin to open and permit the flow of liquid fluid into the evaporator 28. If more liquid is permitted than desired, the vessel 28 expands and closes the ports 41, and if not enough liquid is permitted to enter vessel 28, its pressure is reduced by the compressor and the ports 41 open more by the contraction of vessel 28. In this manner, liquid fluid is fed to the evaporator at a predetermined rate without the least possibility of clogging up of the ports 41 or flooding the vessel 28, as with the old devices.

Some of the lubricant used within the compressor for lubrication and sealing, may be carried into the evaporator in an atomized condition. If not returned to the compressor, the lubricant supply within the latter may become short, resulting in the heating up of the moving parts. To return such lubricant from the evaporator to the compressor, the expansion and contraction of the collapsible vessel is also made use of in the following manner (Figs. 1, 10 and 11).

To the bottom of vessel 28 is attached a double acting pump cylinder 45 covered by a tightly fitting cap 46 which receives the lubricant from the vessel 28 through a number of holes 47 in the bottom of the latter. A double valved piston 48 fits into the cylinder 45 and is rigidly connected to a delivery pipe 49 leading to and connecting rigidly with lubricant return chamber 13, and sliding within a stuffing box neck 50, as a part of the bottom of vessel 28. The operation of the lubricant return pump takes place during the stopping and starting of the apparatus, when the extreme limits of expansion and contraction of collapsible vessel 28 are reached, in which instances the pump piston 48 forms also the limit stop for the collapsible vessel. When stopping, the pressures within the condenser and evaporator equalize, and the vessel 28 expands to its limits. During this expansion all the lubricant which accumulated on top of piston 48 is pressed by the annular ring 51 into the chamber 52 and through the ball valve 53 into the delivery pipe 49, and through the latter into the lubricant return chamber 12.

During this performance the lower chamber 54 fills with lubricant, through openings 55 in the cylinder 45. When the apparatus starts again, and the pressure within the vessel 28 decreases, the vessel 28 contracts and as piston 48 is stationary, the lubricant in chamber 54 is pressed through ball valve 56 into the delivery pipe 49 and from there into lubricant return chamber 13. This action is absolutely automatic and very forceful, so that no lubricant can remain within the vessel 28. If less lubricant than the pump can replace is accumulating within vessel 28, some liquid fluid instead of lubri-

cant will be delivered into chamber 13, and as the latter is under the evaporating pressure, such liquid fluid will tend to cool the compressor by its evaporation. But if more lubricant should accumulate within the vessel 28 than the pump can remove in its regular course, it is only necessary to stop and start the apparatus within short intervals in order to empty vessel 28 of all the lubricant without the least loss to the compressor.

Vessel 28 need not necessarily be located directly under the rotary compressor, but same can be located, just as all the other parts of a complete apparatus, any distance from the compressor, as indicated in the diagram of Fig. 12. In the latter, 60 is the water main line from which the valves 32 are fed and regulated by the rods 36 connecting with the top of collapsible condenser 20. Water line 61 supplies the water jacket of the compressor and collapsible condenser 20, whereas water line 62 supplies the atmospheric condenser 63. The collapsible condenser 20 is augmented by a spiral pipe condenser 64 within the common water jacket 31, and a gas line 65 leading from the bottom of vessel 20 supplies the condensers 63 and 64 with gas to be liquefied. The liquid lines 66 and 67 of the condensers 63 and 64 lead into the main liquid line 26 which connects with the collapsible vessel 28 and regulating valve 27 as described above, but at a certain distance from the base and housing 10.

In like manner leads the return pipe 49 from the lubricant pump within vessel 28 to the distantly located base and housing 10.

The partly vaporized fluid leaves the vessel 28 through pipe 68 to a second evaporator 69, which may be either a room coil, or a freezing tank coil, or the like. The fully evaporated fluid enters the suction chamber within the housing 10 through a vapor pipe 30 as before, only distantly located from the housing 10.

It is evident that the whole arrangement of the apparatus forming the subject of this invention may be made in a great number of different ways without in the least departing from the scope of my invention, and I do therefore not limit myself to the specific arrangements shown in the accompanying drawings and mentioned in these specifications, but claim any and all arrangements within the scope and principles of my invention.

I claim:

1. In combination in a refrigerating apparatus, a vaporizer, a compressor for withdrawing refrigerant vapor from the vaporizer, a condensing chamber having a flexible wall, receiving refrigerant vapor from the compressor, means for delivering cooling liquid to the exterior of the condensing chamber, and means controlled by varia-

tions in the position of the flexible wall of the condensing chamber for controlling the delivery of cooling water to the condenser.

2. In combination in a refrigerating apparatus, a vaporizer, a compressor for withdrawing vaporized refrigerant from the vaporizer, a condenser including a chamber having a flexible wall capable of occupying different positions in response to variations in its internal pressure, means for delivering cooling liquid to the condenser, and a valve actuated by the flexible wall of said chamber for controlling the delivery of cooling liquid by said means.
- 15 3. In an apparatus of the character described, a condensing chamber having a flexible wall exposed to the pressure within the chamber and movable in response to variations of pressure within the chamber, and means for delivering cooling water to the condenser controlled by variations in the position of the flexible wall of said chamber.

4. In an apparatus of the character described, a condensing chamber having a collapsible wall capable of moving in response to variations of pressure within the chamber, means for delivering cooling water to the exterior of said chamber, and means actuated by variations in the position of said collapsible wall for controlling the operation of the first mentioned means.

5. In a refrigerating apparatus, a vaporizer having a flexible cylindrical wall movable in response to pressure within the vaporizer, and a valve for delivering refrigerant to said vaporizer controlled by variations in the length of said wall.

6. In a refrigerating apparatus, a vaporizing chamber, surrounded by liquid to be cooled and having a longitudinally collapsible cylindrical wall movable in response to variations of pressure within the chamber, and a valve for controlling the delivery of refrigerant to said chamber controlled in its operation by said flexible wall.

7. In a refrigerating apparatus, a vaporizing chamber surrounded by liquid to be cooled and provided with a collapsible casing, and a refrigerant delivery valve for delivering refrigerant to said chamber controlled by variations in the collapsible casing occasioned by variations of pressure within the chamber.

8. In a refrigerating apparatus, a vaporizer having a collapsible wall and surrounded by liquid to be cooled, a refrigerant delivery valve for delivering refrigerant to said chamber, controlled by variations in said collapsible wall, a condensing chamber having a collapsible wall and surrounded by cooling liquid, a valve for controlling the delivery of cooling liquid, means actuated by the collapsible wall of said condenser for controlling the operation of said valve, and a compressor for withdrawing vaporized re-

frigerant from said vaporizer and for delivering it to said condenser.

9. In a refrigerating apparatus, a vaporizing chamber having a collapsible wall responsive in its movements to variations of pressure within the chamber, a condensing chamber having a collapsible casing responsive in its movements to variations of pressure within the condensing chamber, means controlled by movements of the collapsible wall of the condenser for controlling the delivery of condensing liquid, means controlled by movements of the collapsible wall of the vaporizing chamber for controlling the delivery of refrigerant to the vaporizer, and means for withdrawing vaporized refrigerant from the vaporizer and for delivering it to the condenser.

10. A refrigerating apparatus comprising a rotary compressor for circulating a volatile fluid; a fluid chamber, vapor chamber and lubricant chamber within said compressor; a longitudinally collapsible condenser containing internally a lubricant separator, the condenser being supported by said compressor and having communication therewith, said condenser operating cooling water regulating means by its expansion and contraction caused by a change of its internal pressure; means for passing the separated lubricant into said lubricant chamber and the fluid into said condenser; a water jacket having inlet and outlet openings for the water surrounding said compressor and said condenser; a longitudinally collapsible evaporator immersed in a non-congealable liquid and containing internally a lubricant pump and an externally adjustable fluid regulator operated by the collapsibility of said evaporator, said compressor and said evaporator being operatively connected by the compressor; means for supplying said fluid regulator from said fluid chamber in the compressor with liquid refrigerant; means for passing the refrigerant vapor from said evaporator to said vapor chamber in the compressor, and means for discharging the lubricant from said pump in the evaporator into said lubricant chamber in the compressor.

11. A refrigerating apparatus comprising a rotary compressor for the circulation of a volatile fluid, having internally a vapor chamber, a fluid chamber and a lubricant chamber; a condenser formed by a longitudinally collapsible vessel supported by said compressor and housing internally a lubricant separator; means for passing the separated lubricant from said separator into said lubricant chamber in the compressor and the separated fluid into the condenser; external cooling water regulating means operated by the collapsibility of said vessel, which is caused to expand and to contract by a change of pressure existing therein; a

common water jacket surrounding said compressor and condenser and having at the bottom a water inlet and near the top a water outlet and internal funnel for overflow; a 5 longitudinally collapsible vessel immersed in a cooling medium, forming an evaporator and operating by its collapsibility a fluid regulator and lubricant pump located within the same, said evaporator having communication 10 with the condenser through the rotary compressor; means for circulating the fluid from said fluid chamber within said compressor to and through said fluid regulator within said evaporator; means for externally adjusting the flow of fluid through 15 said fluid regulator; means for passing the fluid vapor from said evaporator into said vapor chamber within said compressor, and means for discharging the lubricant from 20 pump within said evaporator into the lubricant chamber within said compressor.

12. In a refrigerating apparatus, in combination, a rotary compressor for the circulation of a volatile fluid, having a vapor 25 chamber, a lubricant chamber and a fluid chamber as integral parts of its housing; condensers, one of which consists of a collapsible vessel supported by said compressor and regulating the flow of cooling water 30 by its collapsibility; a lubricant separator within said collapsible condenser and cooled thereby, means for passing the separated lubricant into the lubricant chamber in said compressor and the fluid into said condensers; a water jacket surrounding said compressor and said collapsible condenser; evaporators, one of which consists of a collapsible vessel immersed in a cold carrier and operating by its collapsibility a fluid 35 regulator and a lubricant pump located within the same and means for circulating the liquid fluid, fluid vapor and lubricant, between said collapsible evaporator and the said respective chambers within the said 40 compressor.

13. In a refrigerating apparatus, in combination, a rotary compressor containing separate chambers for liquid fluid, lubricant and fluid vapor; a cooling water regulator 50 forming a part of a condenser and consisting of a collapsible vessel regulating the flow of condensing water by its expansion and contraction; a water jacket surrounding said compressor and cooling water regulator; a fluid regulator immersed in a cold carrier and consisting of a collapsible vessel regulating the flow of liquid fluid to the 55 evaporator by its expansion and contraction and being a part of the evaporator containing the regulating means operated by said collapsible vessel; a lubricant pump located within said collapsible evaporator and operated by the expansion and contraction of the same; and means for circulating the 60 fluid, lubricant and fluid vapor between the 65

respective parts of said immersed fluid regulator and corresponding chambers within said compressor and the condenser.

14. In a refrigerating apparatus, a condensing water regulator forming at least 70 a part of the condenser and consisting of a flexible vessel which controls by its expansion and contraction, caused by a change of its internal pressure, the flow of condensing water to the fluid condenser. 75

15. In a refrigerating apparatus, in combination, a condenser consisting of a plurality of collapsible vessels, one of the latter forming a condensing water regulator which by its expansion and contraction actuates 80 the means for regulating the flow of water to said condensers.

16. In a refrigerating apparatus, in combination, a condenser consisting at least in part of a plurality of collapsible vessels of 85 which one operates by the contraction and expansion caused by a change of pressure in its interior the means for regulating the flow of water to each of said vessels or other condenser. 90

17. In a refrigerating apparatus, a liquid fluid regulator immersed in a cold carrier and consisting of a collapsible vessel forming at least a part of the evaporator, and which is provided with external means for adjusting the internal flow of liquid fluid to said evaporator, said internal means being operated by the expansion and contraction of the walls of said vessel caused by a change in the internal pressure thereof. 95

18. In a refrigerating apparatus, a liquid fluid regulator immersed in a cold carrier and consisting of a collapsible vessel forming at least a part of an evaporator holding in its interior regulating means for the flow 100 of liquid fluid and also means for forcing lubricant from said vessel into the compressor, said means being operated by the expansion and contraction of the walls of said vessel, caused by a change of pressure 110 in the interior of same.

19. In a refrigerating apparatus, a liquid fluid regulator immersed in a cold carrier and consisting of a collapsible vessel forming at least a part of an evaporator and containing a lubricant pump and an externally adjustable fluid orifice, said pump and orifice being operated by the collapsibility of said vessel provided with means for supplying said orifice with liquid fluid and also with means for discharging the contents of said lubricant pump into the lubricant chamber of said compressor. 115 120

20. In a refrigerating apparatus, an evaporator consisting of a plurality of collapsible vessels, one of which forming a fluid regulator containing means for regulating the flow of liquid fluid to said evaporator by the expansion and contraction of its collapsible walls, said expansion and contrac- 125 130

tion being caused by a change of its internal pressure and said collapsible walls being submerged in a noncongealable liquid.

21. In a refrigerating apparatus, an evaporator consisting at least in part of a plurality of collapsible vessels of which one operates an internally located and externally adjustable device for regulating the flow of liquid fluid to said collapsible vessels and

other evaporator by the expansion and contraction of said vessel immersed in a cold carrier, said expansion and contraction being caused by a change of pressure in the interior of said collapsible vessel.

In testimony whereof, I have hereunto 15
subscribed by name this 7th day of October, 1915.

JOHN C. BERTSCH.
